Edwin C. Wood
By his Ally F. K. Richards

UNITED STATES PATENT OFFICE.

EDWIN C. WOOD, OF NEW YORK, N. Y.

STENCIL WITH SELF-SPACING MEANS THEREON.

Application filed July 12, 1923. Serial No. 651,137.

The present invention relates to stencils or similar devices for facilitating the forming of letters or characters by means of cut portions of the stencil and the arrangement 5 of the letters or characters by marking them on a suitable surface in coordinating relation, and one object of the invention is to provide a lettering guide to be used wherever clear, neat manually produced lettering is desired 10 for titles, head lines, addressing, advertising, display or other purposes involving lettering.

Another object is to provide a lettering guide having the same shift distance of the 15 guide for forming all letters or characters which necessitate in their formation by the guide two operations of the pen, pencil or other marking implement used in cooperation with the guide.

20 A feature of the invention is the provision in the guide of a shift opening or shift space and a member slidable therein and contactible by manual pressure thereon with the surface upon which the letters or characters are to 25 be marked, whereby due to sustained pressure on this member it becomes temporarily fixed in its position on said surface and the guide is permitted by manual operation to slide, within the limits of the shift opening 30 or shift space, over the surface to be marked, this sliding of the guide affording shifting movement thereof for forming a letter or character by two operations of the marking implement.

35 The foregoing objects and such other objects as may hereinafter appear, are attained by the invention, one of the possible embodiments of which is set forth by way of example in the subjoined specification and 40 shown in the accompanying drawings forming part thereof, in which Figure 1 is a plan view of the lettering guide.

Figure 2, is a sectional view on the line 2—2 of Fig. 1.

45 Figure 3, is a diagrammatic plan view of the lettering guide for illustrating the formation of a portion of a letter or character by the first operation of a suitable marking element, not shown, in cooperation with 50 a cut of the guide adapted to form said portion of the letter or character and before shifting of the guide.

Figure 4, is a diagrammatic plan view illustrating the formation of the complementary portion of the first mentioned letter

or character by the second operation of the marking implement, not shown, in cooperation with a cut of the guide complementary of the first cut adapted to form the complementary portion of the letter or character, 60 and after shift of the guide.

Figure 5, is a diagrammatic plan view showing the letter or character first formed and illustrating the formation of a letter coordinating therewith formed by a single operation of the marking implement, not shown, and without necessitating operation of the guide shift.

Figure 6, is a diagrammatic plan view showing the two first formed coordinating 70 letters or characters and illustrating the formation of a third coordinating letter or character formed by two operations of the marking implement, not shown, similar to forming the first letter or character and necessitating operation of the guide shift.

Similar reference characters denote similar parts throughout the several views.

The lettering guide comprises a strip 10 of suitable material, preferably transparent 80 and preferably of celluloid, having straight parallel edges. The strip 10 is provided with parallel marginal portions 11 and 12 of equal length and width, the marginal portions being spaced apart by the panel 13 extending for the full length of the strip 10. One face of the panel 13, which may be termed the operatively exposed face, preferably is flush with the surfaces of the marginal portions 11 and 12. The opposite face 90 of the panel 13 is recessed or undercut for its full length and width, whereby, when the device is in operative position on the surface to be marked, the under side of the panel will be spaced away from said surface, to 95 prevent blotting of the ink in the event of use of ink in the marking.

The panel 13 has therethrough a series of cuts generally denoted by 14, some of which provide means for forming by cooperation 100 therewith of a suitable marking implement, not shown, and by one operation thereof a complete letter or character on the surface to be marked, while others of the cuts provide complementary means for forming on 105 said surface parts of a letter or character by the use of said implement by two operations thereof and a shift movement of the guide whereby the complete letter or character is formed, the cuts shown whether single cuts 110

for forming a complete letter or character, or complementary cuts for forming a complete letter or character, being substantially similar in design and arrangement to the 5 cuts shown on the lettering guide described and claimed in my copending application Serial No. 585,261, filed Aug. 30, 1922, and a suitable and preferable marking implement for cooperating with the cuts is described and claimed in my copending application 10 Serial No. 585,262, filed Aug. 30, 1922.

The means for providing said shift movement comprises the shift space 15, arranged 15 at one end of the strip 10, preferably at the right hand end thereof when the guide is in operative position on the surface to be marked, the space 15, as shown, being cut through the panel 13. The pressure member 16 is provided for cooperating with the shift space 15, this member in the present instance being a button having in its periphery a continuous groove 17, the button being sprung into the shift space so that the 20 parallel longitudinal edges of the shift space engage in the groove 17, whereby the strip 10, when the button is held in fixed position, is permitted to be manually moved for a limited distance in either direction, the button having a slight play due to the width 25 of the groove 17 being greater than the thickness of the engaging edge portions of the strip 10, whereby manual pressure on the button to maintain it in fixed position does not interfere with longitudinal movement 30 of the strip 10 in either direction. The distance of movement of the strip 10 in either direction, shown at x , Fig. 4, is slightly greater than the width of the widest letter 35 or character formed by two operations of the marking implement in cooperation with complementary cuts 14 and provides for the necessary shift of the guide 10 for forming all such letters. As an example for showing 40 operation of the lettering guide, assuming that it is desired to place the word "Box" on a desired surface, the guide is arranged in a horizontal position on the surface and suitably maintained therein by means of an 45 adjacent straight edge such as a T-square, not shown.

Referring to Figs. 4, 5 and 6 the guide being provided with suitable reference letters or characters for designating the cuts relative 55 to the formation of letters or characters thereby, and being arranged in position for placing the word at the desired point on said surface, the marking implement is inserted in the cut denoted by 18 for forming by one operation of the implement the stem 60 and lower body portion of the letter B. After formation of these portions of the letter and during sustained manual pressure on the button 16 and manual movement of the strip 10 to the right for the limit of its

movement relative to the button 16, the cut 19 is brought into position relative to the partly formed letter for forming the other body portion thereof by a second operation of the marking implement.

To form the next letter O, the strip 10 is moved bodily until the cut 20 for forming this letter is brought into aligned adjacency to the letter B already formed, the spacing between the letters being left to the eye and discretion of the operator, and the letter is formed by a single operation of the marking implement in the cut 20.

To form the letter X, the strip 10 is moved bodily until the cut 21 is brought into aligned adjacency to the letter O and suitably spaced therefrom and by one operation of the marking implement in said cut one of the inclined sides of the letter is formed; then by movement of the strip 10 to the right 85 as above described relative to the letter B, the complementary cut 22 is brought into position for forming the other inclined side of the letter by a second operation of the marking implement.

Having thus described my invention, it should be understood that there may be modifications thereof and variations therein without departing from the spirit of the invention, or exceeding the scope of the appended claims.

What I claim and desire to protect by Letters Patent is:

1. In a stencil, a long narrow strip positionable on the surface of the material to be marked and having its under surface in contact with the surface of said material, the strip having a series of cuts therethrough for forming letters or characters and being provided with a spacing slot, and stop means 100 slidably engaging in said slot for permitting slidable movement for the length of said slot of the strip on said material, said stop means being engageable with the surface of said material by pressure on the stop means for maintaining said means stationary on the material while said strip is slidably moved thereon, the edges of said cuts providing guiding means for forming letters or characters on the material.

2. In a stencil, a long narrow strip positionable on the surface of the material to be marked and having its under surface in contact with the surface of said material, the strip having an undercut intramarginal portion having cuts therethrough for forming letters or characters and having therethrough a spacing slot, and stop means 120 slidably movable in said slot for permitting slidable movement for the length of said slot of the strip on said material, said stop means being engageable with the surface of said material by pressure on the stop means for maintaining said means stationary on the material while said strip is slidably 125 moved thereon.

moved thereon, the edges of said cuts providing guiding means for forming letters or characters on the material.

3. In a stencil, a long narrow strip positionable on the material to be marked and having its under surface in contact with the surface of said material, the strip having a longitudinal slot therethrough and having a series of cuts therethrough for forming letters or characters on said material, some of said letters or characters being formed by a single marking operation and others of said letters or characters being formed by two marking operations, and stop means slidably movable in said slot for permitting sliding movement for the length of said slot of the strip on said material, said stop means being engageable with the surface of said material by pressure on the stop means for maintaining said means stationary while said strip is slidably moved on the material for the length of said slot for providing the same shift distance of said strip on the material for positioning in letter or character forming relation the cuts for forming letters or characters by two marking operations.

4. In a stencil of the character described, a long narrow strip having cuts for forming

letters or characters and a longitudinal slot therethrough, and means in said slot engaging the strip for permitting slidable movement for the length of said slot of the strip on the material to be marked, said means being engageable by pressure thereon with the surface of the material to be marked for maintaining said means stationary while the strip is slidably moved on said material for the length of said slot.

5. In a stencil of the character described, a long narrow strip having cuts for forming letters or characters and a longitudinal slot therethrough, and a button in said slot having a head, a connecting neck and a base, the head and base respectively engaging the upper and under surfaces of the strip and the neck engaging the slot for permitting slidable movement for the length of the slot of the strip on the material to be marked, said base being engageable with the surface of the material to be marked by pressure on the head of the button for maintaining the button stationary while the strip is slidably moved on said material for the length of said slot.

EDWIN C. WOOD.
